UNITED STATES PATENT OFFICE.

EDWARD HOLBROOK, OF NEW YORK, N. Y.

DESIGN FOR A HANDLE FOR SPOONS, &c.

SPECIFICATION forming part of Design No. 27,848, dated November 16, 1897.

Application filed October 4, 1897. Serial No. 654,094. Term of patent 7 years.

To all whom it may concern:

Be it known that I, EDWARD HOLBROOK, a citizen of the United States, residing at New York, in the county of New York and State of New York, have invented and produced a new and original Design for a Handle for a Spoon, Fork, or Similar Article; and I hereby declare that the following is a full, clear, and exact description of the same, reference being had to the accompanying drawings, forming part thereof.

Figure 1 is a view of the obverse side of a handle, showing my design attached to the bowl of a spoon, the tines of a fork being indicated in broken lines. Fig. 2 is a view of the reverse side of the same.

The leading feature of my design consists in the representation of the stems, leaves, and spikes of the plant known as the "sweet-scented vernal," arranged in an ornamental pattern on the sides of a handle.

In the drawings, A indicates the blade of the handle, B the stem of the same, and C the bowl of the spoon.

On the obverse side of the handle the stems 33 extend from the lower end of the handle and form a raised bead along the edges. The leaves 44 extend from one stem diagonally

to the other and are bunched and twisted as they extend upward and form spaces within 30 which branches of rye 55 and clover blossoms and leaves 6 are represented. The twisted leaves extend along the edges of the blade and inclose the panel 7. On the reverse the leaves 44 also extend spirally across from 35 side to side and inclose the panel 7 of the blade of the handle, and the spikes 88, resembling the seed-head of the sweet-scented vernal, extend diagonally from a bunch of leaves across the side of the handle. The 40 whole presents to the eye the appearance of stems, leaves, and spikes of the sweet-scented vernal grasses or "*Authoxanthum odoratum*" in relief.

Having thus described my invention, what 45 I claim as new, and desire to secure by Letters Patent, is—

The design for a handle for a spoon, fork or similar article herein shown and described.

In witness whereof I have hereunto set my 50 hand.

EDWARD HOLBROOK.
